UNITED STATES PATENT OFFICE.

DAVID J. HUNTER, OF SAEGERTOWN, PENNSYLVANIA.

VENTILATOR FOR TOILET BOWLS OR HOPPERS.

1,173,520.

Specification of Letters Patent. Patented Feb. 29, 1916.

Application filed August 30, 1915. Serial No. 48,049.

To all whom it may concern:

Be it known that I, DAVID J. HUNTER, a citizen of the United States, residing at Saegertown, in the county of Crawford, 5 State of Pennsylvania, have invented a new and useful Ventilator for Toilet Bowls or Hoppers; and I do hereby declare the following to be a full, clear, and exact description of the invention, such as will enable others skilled in the art to which it 10 appertains to make and use the same.

This invention relates to an improved ventilator for toilet bowls or hoppers, and an object of the invention is to ventilate 15 the bowl and the space immediately above the bowl, and to provide hollow hinge connections with the cover and bowl, there being means afforded connected to the hollow hinge connections, for carrying off the odorous gases to the atmosphere. The means 20 for carrying off the gases also having connections with and above the waste pipe to further assist in carrying off the gases.

One of the features of the invention is 25 to provide the hollow hinge connections with means to prevent lateral movement of the seat and the cover of the bowl or hoppers.

In practical fields the details of construction may necessitate alterations falling within the scope of what is claimed.

The invention comprises further features and combination of parts, as hereinafter set forth showing the drawings, and claimed.

35 In the drawings:—Figure 1 is a view in perspective of the improved ventilating system and the hinge connection, as applied to a toilet bowl or hopper. Fig. 2 is a sectional view on line 2—2 of Fig. 1. 40 Fig. 3 is a sectional view through a portion of the hopper and the seat and cover, showing a part of the ventilator. Fig. 4 is a plan view of the hopper or bowl, showing the hinge connection (which is hollow for 45 carrying off the odorous gases) between the hopper or bowl and the seat and cover. Fig. 5 is a transverse sectional view on line 5—5 of Fig. 2. Fig. 6 is a sectional view on line 6—6 of Fig. 4.

50 Referring more especially to the drawings 1 designates the usual form of toilet bowls or hoppers, which is provided with a waste pipe 2 having an off-set pipe 3, which merges into a vent pipe 4. The rear 55 of the hopper or bowl near its upper portion is formed with an extension 5, through

which the flush pipe 6 from the flush box 7, connects. The rear part of the bowl or hopper adjacent its upper edge and above the extension 5 is formed with a transverse 60 flange or extension 8. This extension 8 extends partially upward as shown at 9, and is curved transversely, as shown to form a seat 10, for the transverse pipe 11. Screws 12 are threaded upwardly through the extension 8 and into the pipe 11, to secure the same in place. One end of the pipe 11 has a cover or cap 13 threaded thereto, the other end of the pipe 11 is threaded into a sleeve 14, which in turn is threaded to the 70 pipe 15, which connects or communicates with the vent pipe 4. This vent pipe may extend up through the wall of the house, and terminate above the roof, or it may extend up through the room adjacent one 75 wall thereof and pass through the ceiling and terminate above the roof. The rear edge of the seat of the hopper is curved transversely as shown at 16, to receive and engage the circumference of the pipe 11. 80

The seat 17 is provided with the usual opening the wall of which is channeled or grooved as shown at 18, and the under face of the seat is formed with a groove 19. Fitting the grooves 18 and 19 and being arranged adjacent the under face of the seat is an aluminum plate 20, the part 21 of which constitutes an entire wear plate. The portions 22 of the wood seat overlie the extended flange 23 of the plate 20, so as to 85 prevent the plate 20 from contacting with the person's body. The entire wear portion of the plate 20 is grooved or concaved as shown at 24, to receive the upper edge of the wall of the hopper or bowl. The plate 90 20 terminates as shown at 25 on the outer edge of the seat, thereby preventing the plate 20 from contacting with the person's body. A U-shaped plate 26 arches the pipe 11, and has its upper portion secured at 27 100 and 28 to the upper face of the seat near its rear part. The under part 29 of the plate 26 is secured by screws 30 to the rear flange 31 of the rear part of the plate 20, so that the seat will swing hinged on the 105 pipe 11. It will be noted that the plate 26 adjacent its arch, that is, where it arches over the pipe 11, is formed with an opening 32 so as to permit the upwardly extending part 9 to protrude through the 110 opening and engage the pipe 11. It is to be observed that the opening 32 or cut-

away portion corresponds in width to the length of the part 9, so that the portions 33 of the plate 26 will abut or engage the opposite ends of the part 9, thereby preventing lateral movement of the seat. The edge 34 of the opening 32, when the seat is thrown open engages the rear face of the part 9 as shown at 35, thereby limiting the seat in its open position. The cover or clo-
sure 36 for the seat has its hinges 37, also secured at 28, so that the cover may be raised independently of the seat or raised with the seat when the seat is raised. The rear wall of the seat has an elongated opening 38 corresponding in length and registering with the opening 39 in the pipe 11, when the seat is closed or lowered, so that the odorous gases from the hopper or bowl will be carried off through 38 and 39, and through the pipe 11, and thence outwardly through the vent pipe 4 to the atmosphere. The escape of the odorous gases is accomplished, while the hopper or bowl is in use. However, when the cover is closed, any remaining gases will pass off through the vent pipe in a similar manner, and yet the pipe 11, with the plate 26 constitutes hinge connections between the seat and the hopper.

The invention having been set forth, what is claimed as new and useful is:

1. In combination with a hopper having a flange at its rear adjacent the upper part, said flange having an upwardly extending portion, a pipe secured to said upwardly extending portion constituting a hinge part and having one end closed, and its other end connected to a vent pipe, a hopper seat having a groove in its rear edge to annularly and slidably engage said pipe, a U-shaped plate arching the pipe and having its upper and lower portions secured to the seat, thereby hingedly connecting the seat to the pipe, said U-shaped plate having an opening ad-

jacent its arch part, through which said opening the upwardly extending part of the flange extends, to prevent lateral movement of the seat, said pipe having an opening in its wall adjacent the edge of the seat, the rear part of the seat having an opening in its wall registering with the opening in the pipe, to carry off the odorous gases through the pipe.

2. In combination with a hopper having a flange at its rear adjacent the upper part, said flange having an upwardly extending portion, a pipe secured to said upwardly extending portion, constituting a hinge part and having one end closed, and its other end connected to a vent pipe, a hopper seat having a groove in its rear edge to annularly and slidably engage said pipe, a U-shaped plate arching the pipe and having its upper and lower portions secured to the seat, thereby hingedly connecting the seat to the pipe, said U-shaped plate having an opening adjacent its arch part, through which said opening the upwardly extending part of the flange extends, to prevent lateral movement of the seat, said pipe having an opening in its wall adjacent the edge of the seat, the rear part of the seat having an opening in its wall registering with the opening in the pipe, to carry off the odorous gases through the pipe, one edge of the opening in said U-shaped plate constituting an abutment to contact with the up-standing portion of the flange to limit the seat in its open position.

In testimony whereof I have signed my name to this specification in the presence of two subscribing witnesses.

DAVID J. HUNTER.
